UNITED STATES PATENT OFFICE.

JAMES B. ATWOOD, OF THREE RIVERS, ASSIGNOR TO JOHN W. LABAREE,
OF SPRINGFIELD, MASSACHUSETTS.

LOCK-NUT.

SPECIFICATION forming part of Letters Patent No. 226,263, dated April 6, 1882.

Application filed November 18, 1878.

To all whom it may concern:

Be it known that I, JAMES B. ATWOOD, of Three Rivers, in the State of Massachusetts, have invented a new and useful Improvement 5 in Lock-Nuts; and I do hereby declare that the following is a full, clear, and exact description thereof, reference being had to the accompanying drawings, making a part of this specification, and to the letters of reference marked thereon.

The object of my invention is to cause nuts to gripe bolts so as to prevent dislodgment. To effect this I provide each nut with one or more oblique slots, which extend inward from 15 the face or faces at a point or points between the center of the nut and one or more of its sides to a point near the middle of the nut.

In the accompanying drawings, Figure I represents a perspective view of a nut provided with the said slots according to my invention, and Fig. II represents a transverse vertical section of the same through its axis.

A designates a nut of hexagonal form, with flat faces D and threaded central hole, C, which

receives the bolt. From each face D a slot, B, 25 extends inward nearly to the central line of the nut. These slots begin at diagonally-opposite points between the edges and the middle of the nut, so that their inward course is oblique, and they partly separate from the 30 body of the nut two diagonally-opposite lesser portions. When the nut is turned home the next wrench upon it will cause the partly-separated portions to bend or twist, and the nut will gripe and hold the bolt so as to prevent 35 dislodgment.

Instead of two slots, there may be but one, or there may be more than two. In any case the action will be the same.

Having thus fully described my invention, 40 what I claim as new, and desire to secure by Letters Patent, is—

A nut provided with one or more oblique slots, for the purpose set forth.

JAMES B. ATWOOD.
